UNITED STATES PATENT OFFICE.

HERMAN MELLING, OF JACKSON, MICHIGAN.

DIE-SINKING CUTTER.

1,115,855.

Specification of Letters Patent.

Patented Nov. 3, 1914.

Application filed April 20, 1914. Serial No. 833,154.

To all whom it may concern:

Be it known that I, HERMAN MELLING, a citizen of the United States, residing at Jackson, in the county of Jackson and State 5 of Michigan, have invented certain new and useful Improvements in Die-Sinking Cutters, of which the following is a specification.

This invention relates to improvements in die sinking cutters.

10 The object of this invention is to provide an improved cutting tool for use in die sinking or routing machines.

Further objects, and objects relating to details and economies of structure and operation will definitely appear from the detailed description to follow.

I accomplish the objects of my invention by the devices and means described in the following specification.

20 The invention is clearly defined and pointed out in the claims.

A structure constituting a preferred embodiment of my invention is illustrated in the accompanying drawing forming a part 25 of this specification, in which:

Figure I is a view in side elevation of a structure embodying my invention. Fig. II is a front elevation. Fig. III is a view in rear elevation. Fig. IV is a detail sectional view taken on the line 4—4 of Fig. I. Fig. 30 V is a detail sectional view taken on the line 5—5 of Fig. I. Fig. VI is a detail sectional view taken on the line 6—6 of Fig. I.

In the drawing, similar reference characters refer to similar parts throughout the several views, and the sectional views are taken looking in the direction of the little arrows at the ends of the section lines.

Considering the numbered parts of the 40 drawing, my improved cutting tool consists of a body portion 4 provided with a plane shoulder 2 from which rises the carrying shank 1, said shank having provided 45 therein a beveled notch 3 adapted to be engaged by a set screw or similar device for securing the cutting tool in place. Below the shoulder 2 the body portion 4 is tapered inwardly toward the front of the tool as at 5. The body portion of the tool is provided 50 with a contracted neck 6 and centrally disposed recesses 10, 10 are provided in said neck at each side thereof. The tool is provided with a plurality of cutting knives, the outer cutting edges of which lie on the 55 arc of a circle having its center coincident with the recesses 10. Each of these cutting

knives is provided with cutting edges 9, radiating from the recesses 10 to the outer edges of the knives and these cutting edges are tapered inward slightly toward the 60 outer ends, as clearly shown in Figs. II, III and VI. The sides of each cutting knife are tapered inwardly from each cutting edge to the face of the next knife. The rear 11 of each knife is inclined from the 65 outer edge thereof inwardly to the face of the next succeeding knife.

These cutting tools are especially adapted for use in the die sinking machine shown and described in my prior Patent, No. 70 1,028,125, and this tool is especially used in the forming of dies for drop forging to rout out a half round channel in the die. The tool is secured in place in the die sinking machine in a segment which is rocked back 75 and forth by the action of the machine, the tool being disposed so that the recesses 10, 10 coincide with the center of the segment so that the tool is oscillated as if upon the center 10, 10. As the tool is rocked back 80 and forth in the machine it is fed laterally so that a channel is routed out of the material by the action of the cutting edges.

It will be seen that the cutting edges are inclined inwardly from the center to their 85 outer edge with the result that the end of the channel routed out by these cutting knives is slightly tapered. The object of this is to facilitate the removing of the forging from the dies. The contracted neck 90 6 is provided in order to enable the cutting knives to move through the full half circle, and the recesses 10, 10 are provided to facilitate the dressing of the cutting edges throughout their entire length. When in- 95 inserted in place in the die sinking machine the shoulder 2 limits the movement of the tool in one direction and the tool is securely held in place by means of a set screw engaging the beveled notch 3 by means of 100 which the tool is uniformly brought to the same position.

I am aware that the particular embodiment which I have here set forth is susceptible of considerable variation without departing from the spirit of my invention, and, therefore, I do not wish to be restricted to the same. I have found however that this particular form is to be preferred and, therefore, I desire to claim the same specifically as well as broadly as indicated by my appended claims.

Having thus described my invention, what I claim as new and desire to secure by Letters Patent is:

1. A cutting tool of the class described comprising a body portion having a plane upper surface forming a shoulder, a shank rigid with said body portion and extending at right angles to said plane surface, said shank being provided with a beveled notch 5 therein, a cutting portion, and a neck connecting said cutting portion with said body portion said cutting portion being provided with centrally disposed recesses, and having a plurality of cutting knives 10 with the outer ends thereof disposed on the arc of a circle having its center on the axis of said cutting portion said knives being provided with cutting edges radiating from said axis, and inclined 15 20 inwardly toward the outer ends thereof, and the sides of said cutting knives being tapered inwardly toward the face of the next succeeding knife, all coacting substantially as described for the purpose specified.
2. A cutting tool of the class described comprising a body portion having a plane upper surface forming a shoulder, a shank rigid with said body portion and extending at right angles to said plane surface, a cutting portion, and a neck connecting said cutting portion with said body portion said cutting portion being provided with centrally disposed recesses, and having a plurality of cutting knives 25 30 with the outer ends thereof disposed on the arc of a circle having its center on the axis of said cutting portion said knives being provided with cutting edges radiating from said axis, and inclined 35 40 inwardly toward the outer ends thereof, and the sides of said cutting knives being tapered inwardly toward the face of the next succeeding knife, all coacting substantially as described for the purpose specified.

the next succeeding knife, all coacting substantially as described for the purpose specified.

3. A cutting tool of the class described comprising a body portion having a plane upper surface forming a shoulder, a shank rigid with said body portion and extending at right angles to said plane surface, a cutting portion, and a neck connecting said cutting portion with said body portion, and having a plurality of cutting knives with the outer ends thereof disposed on the arc of a circle having its center on the axis of said cutting portion, said knives being provided with cutting edges radiating from said axis and inclined inwardly toward the outer ends thereof, and the sides of said cutting knives being tapered inwardly toward the face of the next succeeding knife, 50 55 all coacting substantially as described for the purpose specified.

4. A cutting tool of the class described, comprising a shank having a reduced neck and a cutting portion carried thereby the 65 axis of said cutting portion being substantially at right angles to the longitudinal axis of said shank and said cutting portion being provided with a plurality of cutting edges radiating from the axis of said cutting portion and a plurality of transversely 70 extending cutting edges disposed on the arc of a circle having its center on said axis, all coacting substantially as described for the purpose specified.

In witness whereof I have hereunto set my hand and seal in the presence of two witnesses.

HERMAN MELLING. [L. s.]
